(57) **CLAIM**

The ornamental design for a glove, as shown and described.

DESCRIPTION

FIG. 1 is a lower left front perspective view of a glove, showing my new design;

FIG. 2 is a front elevation view thereof;

FIG. 3 is a rear elevation view thereof;

FIG. 4 is a top view thereof;

FIG. 5 is a bottom view thereof;

FIG. 6 is a right side elevation thereof; and,

FIG. 7 is a left side elevation view thereof.

The dash-dash broken lines depict portions of the glove and form no part of the claimed design.

The dash-dot broken lines in FIGS. 1-6 demarcate the boundary of the claimed design and form no part of the claimed design.

The variations in grayscale shading applied to the drawings indicate the contours and variations in surface texture of the claimed design.
